UNITED STATES PATENT OFFICE.

ROBERT J. HELLAWELL, OF NEW YORK, N. Y., ASSIGNOR TO A. G. SPALDING & BROS., OF JERSEY CITY, NEW JERSEY, A CORPORATION OF NEW JERSEY.

EYEGLASS-PROTECTOR FOR BASE-BALL PLAYERS, &c.

No. 924,613.

Specification of Letters Patent.

Patented June 8, 1908.

Application filed June 23, 1908. Serial No. 439,898.

To all whom it may concern:

Be it known that I, ROBERT J. HELLAWELL, a citizen of the United States, residing in the borough of Brooklyn, in the city of New York, in the State of New York, have invented certain new and useful Improvements in Eyeglass-Protectors for Base-Ball Players, &c., of which the following is a specification, reference being had to the accompanying drawing, forming a part hereof.

Base ball players and others engaged in similar sports who are obliged to wear glasses are exposed to the danger of having glasses knocked off and also to the danger of having the glasses broken by a ball or otherwise and of having the face cut by the broken glass and sometimes of having the eye destroyed thereby.

It is the object of this invention to provide a guard which shall prevent the glasses from being dropped, should they be dislodged from their proper position, and from being broken by a ball or otherwise. The device consists of a guard of wire or other suitable material, suitably padded and adapted to rest against the forehead and also against the cheek bones, and provided with suitable means, such as a band or strap to pass about the head and hold the guard in position.

The invention will be more fully described hereinafter with reference to the accompanying drawing in which it is illustrated and in which—

Figure 1 is a view of the guard in front elevation, the upper part of the face of the wearer and eye-glasses being indicated by dotted lines. Fig. 2 is a view thereof in side elevation.

The guard is preferably formed of wire of proper thickness to resist blows which might otherwise dislodge or fracture the glasses of the wearer. It comprises an upper member *a* bent to conform substantially to the forehead of the wearer, a lower member *b*, suitably bent to rest against the cheek bones of the wearer and to straddle the nose, as at *c*, the upper and lower members being united at their ends by vertical members *d*. These upper, lower and vertical members are suitably padded, as indicated at *e*. The upper and lower members are placed apart sufficiently to clear the lenses of the glasses, so that the lenses may stand somewhat in front

of the plane of the upper and lower members without interference. Other guard wires *f* and *g* are secured to the main frame *a*, *b* and *c* and are bent so as to stand beyond the plane of the frame members and to afford a sufficient field of vision between them. They are supported and held in place in the median line by a vertical wire *h*, suitably bent, as clearly shown in Fig. 2, clips *i* being used to secure the wires *f*, *g* and *h* together at the points where they cross. The wires *f* and *g* may also be supported from the frame members by other supporting wires *k* which hold the guard wires out from the frame members so as to avoid interference with the glasses and so also as to protect them from being struck by a ball.

To secure it to the head of the wearer, the guard may be provided with a strap or band, indicated at *l* in Figs. 1 and 2, which is secured to the frame members and passes about the head of the wearer.

It will be understood that wherever "glasses" or "eye-glasses" are mentioned herein it is intended to include all forms of glasses to assist the vision, whether of the pince-nez form or bowed spectacles or otherwise.

I claim as my invention:

1. An eye-glass protector for base ball players etc., comprising upper and lower frame members formed to bear upon the forehead and cheeks of the wearer, and said lower frame member being bent to extend over the nose of the wearer, guard wires disposed between the frame members and secured at their ends to the frame members and projecting beyond the plane thereof, and means to secure the guard upon the head of the wearer.

2. An eye-glass protector for base ball players etc., comprising upper and lower frame members formed to bear upon the forehead and cheeks of the wearer, and said lower frame member being bent to extend over the nose of the wearer, upper and lower guard wires disposed between the frame members and secured to the frame members and projecting beyond the plane of said frame members, a median wire secured to the upper and lower frame members and having the guard wires secured to and supported upon it, and means to secure the protector to the head of the wearer.

3. An eye-glass protector for base ball

players etc., comprising upper and lower frame members formed to bear upon the forehead and cheeks of the wearer and padded, and said lower frame member being bent to extend over the nose of the wearer, upper and lower guard wires disposed between the frame members and secured to the frame members at their ends, a median wire secured to the frame members, clips to secure

the guard wires to the median wire, and means to secure the protector to the head of the wearer.

This specification signed and witnessed this 19th day of June, A. D., 1908.

ROBERT J. HELLAWELL.

Signed in the presence of—

JAMES M. CARRINGTON,
JOHN J. CONLEN.
